(57) **CLAIM**

The ornamental design for an automatic guided vehicle, as shown and described.

DESCRIPTION

FIG. 1 is a perspective view of an automatic guided vehicle showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof; and,

FIG. 7 is a top view thereof.

The broken lines shown in the figures are included for the purpose of illustrating portions of the automatic guided vehicle which form no part of the claimed design.
